CATHODE

Aristote Mavrogenis, Milwaukee, Wis., assignor to
 Radio Corporation of America, New York, N. Y.,
 a corporation of Delaware

Application December 11, 1926, Serial No. 154,199

8 Claims. (Cl. 250—27.5)

This invention relates to cathodes for electron discharge devices and is directed to novel cathodes adapted to be used as electron emitting electrodes or elements in any electron discharge device, for example in the electron discharge device of the type disclosed in my U. S. Patent No. 1,570,444 of January 19, 1926, for Wireless apparatus; and my United States patents for Electron discharge devices, No. 1,616,914 of February 8, 1927, No. 1,629,171 of May 17, 1927, and No. 1,638,499 of August 9, 1927.

In general, this application is a continuation in part of my earlier application Serial No. 652,266, filed July 18, 1923, which has matured into United States Patent No. 1,671,598 of May 29, 1928.

Prior to this invention, the usual practice in making equipotential or indirectly heated cathodes has been to form a metal cylinder and place the heater within the cylinder, such cylinder functioning as the cathode in the electron discharge device, or else to provide a glass tube or its equivalent through which the filament is threaded with a cylindrical metal body surrounding the tube.

In either of these cases, difficulty is experienced due to the fact that in both cases, the active surface of the cathode is very many times greater than that of the coated or uncoated filament customarily used in vacuum tube work. The result of this is that the inter-element capacity of the tube is so great that it precludes its efficient use for high frequency work.

Further, where an insulator is employed between the metal exterior and the filament, it has been found that these insulators are very fragile and are readily broken, so that it is almost an impossibility to mount and handle such a construction without snapping the thin glass or similar tube, and further, as a slight abnormal difference of expansion of the parts is sufficient to break the tube.

Attempts have been made to utilize a porous insulating material, such, for example, as porcelain, but the occluded gases in the porcelain can not be extracted entirely during the evacuation of the tube and it is found that when the tube is used with porcelain that gradually the vacuum is destroyed by the liberation of these occluded gases.

Further than this, when no insulator whatsoever is employed between the metal equipotential or indirectly heated cathode and the heater, it is necessary to have zero potential difference between the heater and the cathode, and also it

is necessary to relatively widely space the heater from the cathode. Clearly, therefore, the heater has to be brought to a higher temperature under these conditions, and is more subject to breaking and is more liable to burn out than under other conditions.

This invention is designed to overcome the defects noted above and objects of this invention are to provide an equipotential or indirectly heated cathode which is so constructed that the heater, the insulator, and the cathode form in reality a unitary non-porous structure, which is extremely rugged and which does not appreciably occlude gases.

A further object of this invention is to provide a unitary construction of equipotential or indirectly heated cathode and heater in which the cathode may be made as small as desired, so that it can replace the ordinary filaments in vacuum tubes, if desired, and can be used in the same manner as these filaments in the various usages of vacuum tubes, such, for example, as wireless reception, rectification, or current limiting work without unduly increasing the inter-electrode capacity of the tube.

Further objects are to so form the equipotential or indirectly heated cathode and heater that the danger of burning out the heater is reduced to a minimum as the entire body is for all practical purposes a unitary structure so that the temperature of the heater need be scarcely more than a few degrees higher than any other portion of the unitary structure.

Further objects are to provide a construction for an equipotential or indirectly heated cathode, such that the evaporation of the filament is prevented and, consequently, to vastly prolong the effective life of the unit, and to further permit the heating of the cathode in air, if desired, in the further steps of coating or treating the cathode, as for instance, where dipping of the cathode into a melted bath, as in one of the possible processes described later in greater detail.

Further objects are to provide a construction of electron-emitting cathode in which the dielectric material is firmly bound to an element of the cathode to thus reduce the size of the cathode, and materially reduce the time required to bring the cathode up to operating temperature.

A further object is to provide a construction of electron-emitting cathode in which the mass of dielectric material required is very small, whereby a very efficient transfer of heat from the heater to the electron-emitting surface is obtained.

Further objects are to provide a construction in which a coating of dielectric material is firmly bound to one of the elements of the electron-emitting cathode, and which thus produces a cathode of small size and small mass with all of the resulting advantages, and in which a dielectric coating is formed which is mechanically strong and cannot be damaged by the elements of the electron-emitting cathode.

10 Further objects are to provide a novel method of forming the conducting and electronically active coating upon the surface of the cathode, and forming the connections to such coating.

15 Embodiments of the invention are shown in the accompanying drawings in which:

Figure 1 is a view partly in section of one form of cathode, such view being very much enlarged;

Figure 2 is a detail to a further enlarged scale of the lower portion of Figure 1;

20 Figure 3 is a view corresponding to Figure 1 of a modified form;

Figure 4 is a detail of the upper portion of the structure shown in Figure 3;

Figure 5 is a detail of a further modified form;

25 Figure 6 is a view partly in section showing the type of the tube with which the cathode is used.

Referring to Figures 1 and 2, it will be seen that the cathode comprises a filamentary heater 1 which is formed of tungsten, tantalum, molybdenum, platinum, nickel or other suitable metal or alloy thereof such materials as disclosed by way of example in my copending application Serial No. 140,848, filed October 11, 1926, and is preferably formed of a fine wire coiled into a minute helix. This heater is coated with a refractory and insulating coating, as indicated at 2, and such coating is provided with an enlargement 3 about centrally of each of the branches of the V-shaped cathode. The coating may be applied or formed by the methods disclosed in my co-pending application, Serial No. 140,848, for cathodes and method of making same filed October 11, 1926. As disclosed in my co-pending application, the dielectric material in the form of a paste or of any desired consistency, is applied to the filament. The coated filament is heated or baked, and preferably a current is passed therethrough to aid in this heating. This process is preferably carried on at a rate to prevent bubbling or unnecessary agitation of the insulating coating. Further, the coating is such that it forms a strong, durable, non-cracking, non-blistering and non-hygroscopic coating over the filament. Obviously, since the dielectric material is baked in situ, that is, on the filament, it is hardened adhesively or fused on the filament. Hence, there is obtained an intimate binding contact between the dielectric material and the filament. This coating is solid and firmly adherent to the heating member. It is of high insulating and heat resisting characteristics. After the coating has been formed, the conductors, 4, 5, and 6 are wrapped about the insulating sheath 2 and thereafter, a metal or conducting coating 1 is formed 65 with the conductors 4, 5, and 6 embedded therein. Also, it is to be noted that a thermionically active coating 8 is formed on the metal coating 7.

These coatings are formed in the manner hereinafter described in detail.

70 My co-pending application Serial No. 140,848, filed October 11, 1926, discloses by way of example, certain materials that may be used in forming the insulating coating as will appear hereinafter.

75 It is to be noted that the form, shape,

length and nature of the insulating coating may be varied to meet any particular demand in connection with the form, type, shape, nature, physical condition of the outside or surface of the filament, heater or conductor, as well as in connection with the length, portion, or portions of such filament, heater, or conductor to be coated with such an insulating coating.

In forming the insulating sheath or coating 2, it is preferable to use basic compounds for the 10 coating, such as molybdenum oxides, or hydroxides, or nickel oxides, or nickel hydroxides, or a mixture of them in which a small percentage of tungsten oxide may be added, if so desired. Further, any suitable variety of silica, such as quartz, 15 or a suitable silicon compound such as silicic oxide, feldspar, that is, a double silicate of aluminum, potassium, sodium, magnesium or calcium, or the like may be used. All of these materials are very finely ground, and, of course, prefer- 20 ably chemically pure ingredients are used.

To the above described base high heat resisting and insulating materials, a small percentage of other materials may be added in order to make it more compact, elastic, mechanically strong, and 25 non-porous, and free from cracking, blistering, or the like, and so that an air-tight strongly adherent coating may be formed. Such materials are, for instance, sodium oxide, usually used in its compound form, tetraborate of sodium or 30 borax, sodium nitrate, or the equivalent compounds of potassium, lead oxide, zinc oxide, double fluorite of sodium and aluminum, or calcium fluorite. Some of these materials may somewhat increase the coefficient of expansion 35 and form powerful adherent agents during heating. Other compounds may be used to vary the coefficient of expansion such, for example, as boric oxide.

It is evident, that any other suitable compound, 40 or compounds, may be employed without departing from the spirit of this invention.

It is also obvious that any other suitable form of adherent agents or binders of a different chemical nature from those mentioned above, may be 45 wholly or partially substituted for the above mentioned adherent agents or binders.

It is also found advantageous to add a small percent of finely ground clay. The clay can be very finely ground in water and acts as a suspension agent to keep the non-soluble material floating throughout the entire liquid.

The electric conductor to be used as a heater for an electron-emitting cathode, is surrounded by the selected material. Heat is applied in any 55 suitable manner, as by passing a current through the conductor. The temperature employed is sufficient to cause the material or materials to adherently bind to the conductor, and may fuse, either partially or wholly, the material or ma- 60 terials employed.

The heating process may be carried on in a non-oxidizing medium, such, for example, as in a vacuum, or in open air or any suitable atmosphere. However, if the process is followed, the 65 coating will nevertheless adherently enclose the filament, as for example by fusing around the filament.

The ends of the V-shaped heater are connected to terminals 9 which are of relatively 70 heavy wire or otherwise made materially heavier and stronger than the filamentary heater.

The conductors 4, 5, and 6, are very firmly embedded in the conducting coating and, conse- 75

quently, form a very secure and reliable electrical connection therewith.

In the form of the invention shown in Figures 3 and 4, the same type of filamentary heater is employed, as indicated at 10. This heater is similarly coated with an insulating sheath 11 formed with enlargements 12. Further, it is to be noted that the terminal connectors 13 in this form of the invention, have their ends embedded in and surrounded by the insulating sheath or coating 11. It is to be noted further, particularly from Figure 4, that the central part of the filamentary heater 10 is connected to a terminal 14 which also is embedded in the insulating sheath and preferably such insulating sheath is enlarged at this portion or thickened, as indicated at 11', and shown in Figure 4. A further difference from the previously described form resides in the fact that the upper portion of the insulating sheath 15 is provided with two distinct and separate coatings formed jointly of a conducting coating 15 and a thermionically active coating 16, as previously described, but with the two portions thereof formed as separate entities and joined by the connector 17. This connector also may be carried by a support or conductor 18, if desired. This cathode is adapted for use in an electron discharge device having full wave rectification as disclosed in my United States Patent No. 1,629,171, noted above. In the form shown in Figure 5, the enlargements indicated at 3 and 12 in Figures 1 and 3, are omitted and instead, the conducting sheaths 19 and their coatings 20 stop short of each other and are spaced a material distance apart. The insulating sheath or coating 20 continues throughout the heater of substantially the same diameter, and is devoid of enlargements intermediate its ends.

In each form of the invention, it is to be noted that the cathode is multiple or compound in that it provides three distinct cathodes, for example, as indicated at A, B, and C in each of the figures. The cathode "B", as shown in Figure 6, may be used for the cathode of the audion; the cathode "C", as the cathode of the rectifier, and the cathode "A", as the cathode of the current limiting device. The plate of the audion is indicated by the reference character 21, that of the rectifier by the reference character 22, and that of the current limiting device by the reference character 23. The grid of the audion, as indicated at 24, is carried by suitable supports extending upwardly from the glass bridge piece 25 of the evacuated tube 26, a suitable base 27 provided with prongs being also provided as described in detail in my above noted patents.

It is to be understood that any suitable form of supports may be used for the several portions of the apparatus. For example, as shown in Figure 6, the plates 22 and 23 may closely enclose their cathode and may have their ends turned outwardly, as indicated at 28 and 29, and rolled about and secured to the appropriate supporting rods. Similarly, the plate 21 of the audion may be formed of two similar members, and may have its ends rolled about the supports therefor, as indicated at 30 in Figure 6.

The tube is shown merely to bring out the relative position of the several cathodes and to show the manner in which the multiple or compound cathode cooperates with and adapts itself to use in the vacuum tube in which a rectifier, current limiting device and audion are employed.

It is to be distinctly understood that the lead-in conductors or terminal members are preferably

formed relatively stiff so that they may act as supports for the cathode.

Further, it is to be distinctly understood that although the terminal conductors have been shown as embedded, in one form of the invention, that obviously, they may be embedded in the dielectric coat of the heater in any of the several forms shown.

The method and apparatus for forming the insulating coating form the subject matter of my above noted copending application S. N. 140,848.

The metallic or other electrically conducting coating is formed on the outer side of the insulating coating which may embed or enclose the heater wholly or partially and which is adhesively bound to the heater. The metallic coating may be formed in a number of different ways. For example, it may be formed by applying a solution of silver compound, nickel chloride, or electrically conducting chlorides of other metals. This coating is changed into metal by means of heat, preferably by heating the apparatus within a vacuum.

Other modes of coating the device to form the metal equipotential or indirectly heated cathode may comprise the use of a colloidal solution of the metals to be subsequently baked thereon. Thereafter, a third coating is formed on the metal coating and is indicated by the reference character 8 in Figure 2. This third coating is formed of calcium, barium, strontium, thorium, or similar low electron affinity oxides or hydroxides, or their compounds. This coating may be prepared by using a solution of such materials or their compounds and simply dipping the equipotential or indirectly heated cathodes therein and leaving them to dry or else by using a melted mass of these materials.

A further method of forming both the metal equipotential or indirectly heated cathode and the coating thereon may be followed. For example, a solution containing a mixture of the metallic compounds used for the main cathodes with one or more of such low electron affinity oxides may be prepared and the insulating coating may itself be coated with this solution. Thereafter, the equipotential or indirectly heated cathode may be mounted in its normal and permanent position inside the tube and brought above its normal operating temperature by means of the heater sufficiently to melt the low electron affinity oxides. It is found that when this heating takes place, that the oxides come out on the surface and form an efficient coating while the metal inner sheath is also formed. By bringing the heater to a temperature above its normal operating temperature, it has been found that the metal is partially fused and the mass of oxides and partially melted metal stratify, and the oxides come out on the outer side and the metal cohesively binds itself, both to the oxides and to the insulating coating.

Further, a mixture of the low electron affinity compounds and colloidal solution of the proper metals may be made and applied directly to the insulating sheath, subsequent heating being employed in the manner described above.

It is to be noted also that there is no danger of burning out the heater or filament as it is coated by the insulating strongly adherent sheath. Further, the evaporation of the filament is practically zero as the opening in the helix is so small that no portion of the filament escapes during heating. The filament can be heated even in the open air, if desired, although, in view of the

fact that the oxides enumerated above are hygroscopic, it is preferable to heat the device in its permanent mounting within the tube and while the tube is being exhausted.

5 Other materials may be used for forming the metal coating and oxide coating. For example, chlorides of platinum, palladium, rhodium, ruthenium, iridium, and osmium, may be used, or chlorides or other compounds of nickel, iron, cobalt, or any mixture of two or more of these. Further, to reduce the expense of manufacture, the solution may be mixed with metal in its powdered form, such as silver, tungsten, molybdenum, tantalum, iron, or nickel, or any mixtures of these. Preferably, these metals are suspended in a colloidal form. Further, if desired, a small proportion of binding agent may be used as a metallic lead oxide or calcium chloride or any mixture thereof. These mixtures can be applied 10 either mixed in a cold solution or else they may be melted to form a melted bath into which the coated heater is dipped. The low affinity oxides or alkaline compounds may be added to this mixture at the time it is formed, if desired. As a 15 rough illustration of a few of the relative amounts that may be used in groups, the following is submitted:

For example, 6% oxides, 93% chlorides, and 20 1% binding agent can be used satisfactorily. Another mixture may consist of 49% of a mixture of oxides and chlorides in the relation of 10% oxides to 90% chlorides. To this 49%, 50% of metals, as described above, and 1% binding agent can be added.

25 35 A further process that can be followed with these cathodes is to employ nickel, silver, gold, platinum, palladium, or others of the metals mentioned above containing compounds electrically conducting, and form a paste of these compounds using water, alcohol, or any liquid in which such 40 45 compounds are soluble, or else the metals mentioned above may be employed in the colloidal form and applied as a colloidal solution to the dielectric material. It is intended that in these cases the liquid is either wholly absorbed or evaporated prior to using the cathode.

A further method is to employ any of the metals just mentioned in the form of a liquid bath in which the cathode is dipped. Further, the low 50 55 affinity oxide coating may be formed upon the metal coating by dipping such partially coated cathode into a melting bath of alkaline metals or their oxides, or other compounds, particularly the metals, such as barium, strontium, and calcium. Further, the melted solution or even the mixture may have both the noble metal, as well as the low electron affinity oxides therein.

60 65 A further method may be followed which consists in dipping the cathode into a melted solution containing approximately ten percent of alkali metals and ninety percent of the main metals mentioned above. Thereafter, the cathode, after cooling, is baked in a vacuum to the melting point of the oxides, whereby a film of oxides covers the whole of the cathode structure and both the metallic and thermionically active coatings are formed.

70 75 It is to be noted that other compounds may be used in place of the low electron affinity oxides. Compounds of the alkaline metals may be used and heated to reduce them to low electron affinity oxides. For example, the cathode may be dipped in a solution of a suitable barium compound and subsequently heated to form barium oxide.

It is to be noted that a very firm, reliable, and practical form of equipotential or indirectly heated cathode has been produced by this invention, and that a very simple method of forming the active coating has also been disclosed.

5 It will be seen that the cathode may be used as an ordinary cathode, if desired, in vacuum tube work, or may be used as the composite cathode described above. In case it is used merely as a single cathode, obviously the separate portions, 10 such as indicated at A, B, and C, in the drawings, are not formed, but either a single straight cathode is formed, or else the entire surface of the cathode forms one continuous member.

15 It will be seen further that the cathode may be very readily handled and easily mounted in the tube without danger to the parts of the cathode, as it is materially sturdier than the heretofore known forms.

20 Further, it will be seen that the cathode is not subject to breaking due to changes in temperature or relative differences in temperature of the several parts.

25 It is obvious that the filament, or heater may be of any type or shape desired, depending upon the particular type of tube with which it is used. Also it is clear that the characteristics of the dielectric material will be varied to correspond to the particular type of filament or heater with which it is associated.

30 35 It is to be understood that this invention is not limited to any particular form, shape, size or type of equipotential or indirectly heated cathode unit or structure.

The term "coating", when used alone, is intended to mean a layer of any substance covering another.

The term "adhesively" is intended to mean steadily or firmly attached.

40 Although the invention has been described in considerable detail, such description is intended as illustrative rather than limiting as the invention may be variously embodied and as the scope of such invention is to be determined as claimed.

I claim:

1. A solid equipotential cathode comprising a thermionically active metal coating, a heat radiating element located within the metal coating, a dielectric refractory body fused as a permanent and adhesive coating on the heat radiating element and hermetically enclosing said heater and adhesively engaging said heater and the metallic coating, and electric lead-in conductors connected to the terminals of said heat radiating element, said lead-in conductors being relatively rigid and acting as supports for said cathode, said lead-in conductors being enclosed in the dielectric body portion.

2. A multiple, continuous, solid equipotential cathode comprising a single heating body, a refractory electrically insulating material fused on said heating body and forming a linearly extending and continuous coating on the entire length of said heating body, and hermetically enclosing said heating body, and a plurality of separate 65 conducting and thermionically active coatings on said refractory insulating material, each of said conducting coatings being electrically distinct and separate from any other coating and from the heater body, whereby all said coatings form a 70 permanent, continuous and adhesive whole.

3. An electron discharge device comprising a plurality of cooperating electrodes, at least one of said electrodes being an indirectly heated electron-emitting cathode comprising a metallic 75

5 sleeve serving as an electron-emitter and a heater surrounded substantially by said sleeve, but maintained out of direct electrical contact therewith, said heater comprising a two-leg electric conductor anchored about its center and connected at its ends to lead-in conductors and comprising an insulating, high heat-resisting coating formed on at least said legs and at least physically adhesively bound thereto.

10 4. An indirectly heated electron-emitting cathode comprising a metallic sheath serving as a cathode member, a heat-emitting element substantially surrounded by said metallic sheath, an insulating, refractory coating at least partially fused on said element and thereby adhesively bound to said element and closely in contact with said metallic sheath, and an electric lead-in conductor connected to a terminal of said heat-emitting element and having its point of connection 20 embedded within a portion of said insulating coating.

15 5. An indirectly heated electron-emitting cathode comprising a metallic cathode member and a heater for the same and adjacent thereto, said heater comprising a two-leg electric conductor having a portion projecting from between said two legs and extending beyond said metallic cathode member and designed to be anchored to a support, said conductor being enclosed, at least 30 at certain portions of its extent, in an insulating, high heat-resisting coating at least partially fused thereon.

35 6. An indirectly heated electron-emitting cathode comprising a filament having a plurality

of legs, a continuous, refractory, insulating coating at least partially fused both on at least a part of said legs and on a portion connecting one leg with the succeeding one, an outer metallic coating formed on said insulating coating and serving as a cathode member, and an electric lead-in conductor having a portion embedded within said metallic coating to thus provide electrical connection therewith.

5 7. An electron discharge device having an electron-emitting cathode sealed therein and comprising an electrically conductive sleeve having an outer side capable of being treated for electron-emitting purposes and serving as an electron-emitter, a heating element substantially surrounded by said conductive sleeve, but maintained out of direct electrical contact therewith, for heating said conductive sleeve, lead-in conductors, said heating element comprising two legs and being anchored at some point between its legs 20 and being connected at its ends to said lead-in conductors, and an insulating, refractory, solid material therebetween and substantially enclosing at least a part of said legs.

10 8. A V-shaped heater wire, conducting leads 25 connected to its ends, a refractory coating fused to and surrounding each leg of said wire and the connecting portion of said leads, and a conducting sleeve surrounding each leg of the refractory coating, said sleeves being joined integrally together at the bend of the coating, and a terminal wire connected to the sleeve at said bend.

15 ARISTOTE MAVROGENIS.
